[57] CLAIM

The ornamental design for a bottle, substantially as shown and described.

DESCRIPTION

FIG. 1 is a front elevational view of a bottle showing my new design;

FIG. 2 is a side elevational view looking at the right side of FIG. 1;

FIG. 3 is a top plan view thereof, on a reduced scale; and

FIG. 4 is a bottom plan view thereof on the same scale as FIG. 3.

The rear elevational view of the bottle is plain and unornamented.
